UNITED STATES PATENT OFFICE.

FREDERICK J. DOWLE, OF TRENTON, NOVA SCOTIA, CANADA, ASSIGNOR OF ONE-HALF
TO EDMOND HAZEN HENDERSON, OF PARRSBORO, NOVA SCOTIA, CANADA.

STILSON WRENCH.

1,231,575.

Specification of Letters Patent. Patented July 3, 1917.

Application filed September 28, 1916. Serial No. 122,759.

To all whom it may concern:

Be it known that I, FREDERICK J. DOWLE, a British subject, residing at the town of Trenton, in the county of Pictou, in the Province of Nova Scotia, Dominion of Canada, have invented new and useful Improvements in Stilson Wrenches, of which the following is a specification.

My invention relates to improvements in Stilson wrenches which are used chiefly for grasping and holding on round surfaces such as a pipe, and the objects of my invention are first, to use the power applied solely as leverage in increased grasping power as well at the same time. Secondly, to allow of a quick release of the jaws, and thirdly, to allow of several sizes being grasped without adjusting any of the parts.

I attain these objects by the mechanism illustrated in the accompanying drawing in which—

Figure 1 is a side view of the machine. Fig. 2 is an edge view of Fig. 1. The light broken lines show the supplementary jaw, the guide sleeve and the handle as they appear in operation.

Similar letters refer to similar parts throughout the several views.

In the drawing *b* is the adjustable jaw the stem of which is oblong in cross section and is partially threaded, the enlarged part being serrated to prevent slipping when in operation. *c* is the cage which holds in position the nut *f* which is threaded to match the adjustable jaw *b* which passes through the cage *c* and is adjustable therein by means of the nut *f*. *d* is the guide sleeve which is movable on the stem of the adjustable jaw *b*. *a* is the handle through which the power is applied. At the pivoted end it is of an even thickness of the stem of the adjustable jaw *b* and is pivoted in the cage *c* at *x*. *e* is the supplementary jaw, the grasping part of which is serrated and is the same in thickness as the cage *c* and the guide sleeve *d*, into which sleeve it is fitted and pivoted at *n*. It is also fitted against the cage *c* and clasps the thin part of the handle *a* and is pivoted to it at *h*. The parts *c*, *e*

and *d* when held in place by the spring *g* 50 present an even jointed surface. The function of the spring *g* is to quickly release the grasp of the jaws when the pressure is removed, and to throw the handle back to its original position.

When the wrench is being operated the handle, the supplementary jaw, and the guide sleeve are carried in the direction indicated by the light broken lines, showing that any increase of power applied results in 60 increased grasping pressure on the jaws.

Having illustrated and described my invention what I claim and desire to secure by patent is:

1. In a wrench, the combination of a cage, 65 a jaw having a partially threaded shank integral therewith passing through and carried by said cage, a nut carried by said cage adapted to engage and adjust said shank and jaw, a lever hinged to said cage, a supplementary jaw pivotally attached to said lever and movable thereby, and a guide 70 slideable on said partially threaded jaw, pivotally attached to said supplementary jaw and adapted to support the free end of the 75 same; substantially as described.

2. In a wrench the combination of a cage, a jaw adapted to hold on round surfaces having a partially threaded shank integral therewith passing through and carried by 80 said cage, a nut carried by said cage adapted to engage and adjust said shank and jaw, a lever hinged to said cage, a supplementary jaw adapted to hold on round surfaces pivotally attached to said lever and movable 85 thereby, and a guide sleeve slideable on said partially threaded shank pivotally attached to said supplementary jaw and adapted to support the free end of the same; substantially as set forth.

3. In a wrench the combination of a jaw adapted to hold on round surfaces having a partially threaded shank integral therewith, a cage adapted to carry and guide said shank and jaw, a nut carried by said cage 95 adapted to engage and adjust said shank and jaw, a lever hinged to said cage, a supplementary jaw adapted to hold on round

surfaces pivotally attached to said lever and movable thereby, a guide sleeve pivotally attached to the free end of said supplementary jaw movable on said partially threaded shank, with a plate spring attached to said supplementary jaw and tending to maintain said lever and shank in a parallel

position; all substantially as described and for the purpose specified.

FRED J. DOWLE.
